(57) CLAIM

The ornamental design for a shopping cart, as shown and described.

DESCRIPTION

FIG. 1 is a top, front, left side perspective view of a shopping cart showing our new design;

FIG. 2 is a left side elevation view thereof;

FIG. 3 is a top plan view thereof;

FIG. 4 is a front elevation view thereof;

FIG. 5 is a right side elevation view thereof;

FIG. 6 is a bottom plan view thereof;

FIG. 7 is a rear elevation view thereof; and,

FIG. 8 is a top, back, right side perspective view thereof. The broken lines shown in the figures are for the purpose of illustrating portions of the shopping cart which form no part of the claimed design.
